[57] CLAIM

The ornamental design for a bubble insert package for cables, as shown and described.

DESCRIPTION

FIG. 1 is a front elevation of a bubble package for cables showing my new design;

FIG. 2 is a right side elevation thereof;

FIG. 3 is a left side elevation thereof;

FIG. 4 is a top plan view thereof;

FIG. 5 is a bottom plan view thereof;

FIG. 6 is a rear elevation thereof; and,

FIG. 7 is a fragmentary sectional elevation thereof; taken along line 7—7 of FIG. 1.

FIG. 1

FIG. 2

FIG. 3

FIG. 4

FIG. 5

FIG. 6

FIG. 7
